EMERGENCY TRIP MECHANISMS

John Blair Stevens, Glenside, Pa., assignor to Schutte and Koerting Company, Cornwells Heights, Pa., a corporation of Pennsylvania

Application February 8, 1952, Serial No. 270,656

3 Claims. (Cl. 74—2)

The present invention relates to safety devices for valves, and more particularly to emergency trip mechanisms for throttle and like valves.

In power plant practice, an emergency trip mechanism is normally associated with the throttle valve of a steam turbine. Under certain operating conditions, the pull-out force, the force necessary to actuate the trip mechanism is substantial. Consequently, the trip mechanism may be subject to a delay in actuation due to this excessive force. It is desirable therefore to have the pull-out force as small as possible, but it has been found that when this force is reduced below a certain minimum, the trip mechanism may be actuated inadvertently by power plant vibrations transmitted to the mechanism through pipes or through the building itself.

The present invention contemplates vibration-proof means whereby the pull-out force is relatively small and substantially constant under all operating conditions, whereas the hooking force is high and steady, and is adjustable to permit actuation of the mechanism by and only by application of a force of predetermined value.

More specifically a primary object of my invention is to provide a trip mechanism wherein the pull-out force is essentially independent of the operating conditions under which the valve may be required to operate.

A further object is to provide a trip mechanism of the stated class having novel means for regulating the pull-out force.

These and other objects of the invention hereinafter appearing will find amplification in the attached specification, of which the attached drawings constitute a part.

In the drawings:

Fig. 1 is a side elevational view partially in section of a trip mechanism according to my invention;

Fig. 2 is a front elevational view of the mechanism;

Fig. 3 is a sectional view taken along the line 3—3 of Fig. 1;

Fig. 4 is an enlarged fragmentary section view illustrating certain structural features of the mechanism;

Fig. 5 is an enlarged sectional view taken along the line 5—5 of Fig. 1;

Fig. 6 is a perspective view of one element of the mechanism; and

Fig. 7 is a fragmentary view illustrating a structural feature of my mechanism.

Referring more specifically to the drawings and particularly to Fig. 1, the valve (not shown) is actuated by vertical movement of a stem 11 which is threaded into a stem carriage 12 as indicated at 13. The carriage 12 is slidably mounted in a fixed sleeve 14, and is pivotally attached by pins 16, 16, which extend through slotted openings 19, 19 in the sleeve, to a latch arm 15, as illustrated in Fig. 7. The latch arm 15 is normally maintained in an elevated position by engagement with a hook assembly 17, hereinafter specifically described. Counterclockwise rotation of the stem 11, by manual or other means not shown, will elevate said stem and disengage the valve head from its seat, thereby opening the valve.

2

Clockwise rotation, on the other hand, will force the valve-head into its seat effecting closure of the valve. Upon actuation of the trip mechanism when the valve is open, the hook assembly 17 will be caused to disengage the latch arm 15 to allow downward movement of the carriage 12 which will similarly effect closure of the valve.

The trip mechanism comprises in combination the hook assembly 17, the carriage 12, an actuating spring 18, and the latch lever 15 which is pivotally attached at its right end to a collar 21 by a connecting link 22. At the left hand side, collar 21 is bifurcated, and the spaced bifurcations 23, 23 are provided each with an upward projection 24. The arms or bifurcations 23 carry a support bar 25 and the projections 24 carry a limit bar 26.

The hook assembly 17 comprises a hook bracket 28, which is pivotally attached to the collar 21 through the medium of a pin 27 to which the bracket is keyed, a connecting arm 29 fixed to the pin, a connecting rod 31 pivotally attached to the upper end of the connecting arm 29, and a hook roller 32 rotatably mounted in the lower portion of the hook bracket 28 as best shown in Figs. 4 and 5. The hook bracket 28 as shown in Figs. 4 and 6 is formed with a pair of upwardly projecting ears 35 and 36 and an outwardly extending arm 37 with an aperture 38 at the outer extremity thereof and an upstanding rounded lug 10 at each side of the aperture.

The hook bracket 28 is resiliently connected to the support bar 25 by a regulating bolt 33 co-acting with a regulating spring 34. The spring tends to turn the hook bracket 28 clockwise as viewed in Fig. 1, but the bracket may be moved counterclockwise about its pivot 27 against the pressure of the regulating spring 34 by actuation of the connecting rod 31. Freedom for such movement is insured by mounting the bracket in a pair of anti-friction bearings 40 in the arms 23. The movement is limited to small angles by contact of the ears 35 and 36 with the limit bar 26. As illustrated in Fig. 4, the lower portion of the hook bracket 28 is hollow, forming a lip 41 underlying the hook roller 32 which is rotatably mounted in the bracket by means of a pair of anti-friction bearings 42. The hook roller may be mounted on the latch arm without departure from the present invention. In this arrangement the roller would engage the lip of hook bracket whereby the mechanism would operate in substantially the same manner as the illustrated mechanism.

In the operation of the device, the valve (not shown) is opened by counterclockwise rotation of the valve stem 11, thereby raising the stem in and with respect to the carriage 12 which is supported in an elevated position by engagement of the recessed end of the latch arm 15 with the hook roller 32 as described above. If a requirement arises for quick closing of the valve, the connecting rod 31 is moved to the right to position shown by the broken lines in Fig. 1. The resulting angular movement of the bracket 28, limited by contact of the ear 36 with the limit bar 26, swings the hook assembly 17 and therefore the hook roller 32 out of engagement with the latch arm 15. This disengagement of the arm 15 permits the stem carriage 12 to move downwardly under pressure of the actuating spring 18, the pins 16, 16 sliding downwardly in the recesses 19, 19 of the sleeve 14, until the assembly assumes the position shown in broken lines in Fig. 1.

As recited above, the pull-out force of the conventional trip mechanism under certain operating conditions is substantially greater than the force required under normal conditions. This variation in pull-out force is caused in large degree by internal unbalances acting on the stem and transmitted to trip lever by a relatively high friction factor. In a device according to the present in-

vention, the friction factor is reduced to such an extent that the forces exerted on the stem have substantially no effect on the pull-out force required to actuate rod 31.

Regulation of the pull-out force is provided by regulating bolt 33 and the spring 34. The head of the bolt 33 seats in effect upon the upper curved surfaces of the ears 10 which provides a constant bearing for the head over the entire range of angular displacement of the hook bracket 28. A nut 43 is provided on the regulating bolt 33 to confine the spring 34 between the support bar 25 and the nut 43. Tightening of the nut 43 will compress the spring 34 and increase the force required to rotate the hook bracket 28 about its pivot 27, which by reason of the substantially complete absence of friction in the hook assembly as a whole, is the pull-out force. By adjusting the nut 43 on the regulating bolt 33, the pull-out force may be regulated with precision to a required minimum value without danger of inadvertent actuation by transitory impulses such as vibration.

While this invention is particularly adaptable to heavy duty valves, it is not contemplated that the device be limited to use on such valves alone, and the invention may find useful application to other valves, or to mechanisms of similar nature and purpose.

I claim:

1. Emergency trip mechanism for valves, said mechanism comprising a pivotally mounted pressure-biased valve-supporting lever, a pivoted member arranged to engage a free end of said lever and to support the lever in retracted position against said biasing pressure, means for applying force from external source divorced from said lever to angularly move said member about its pivot to release the said lever, a spring operatively connected to said member independently of the release means and normally retaining the member in lever supporting position, said spring thereby acting in opposition to said release force which applied from the external source to move said member, means for adjusting the spring to regulate the pressure opposing the said release movement, and antifriction means affording a seat for the lever on said member.

2. Emergency trip mechanism for valves, said mechanism comprising a pressure-biased valve-supporting member, a second member arranged to engage and support said valve-supporting member in retracted position against said biasing pressure, means for applying force from external source divorced from said valve-supporting member to relatively displace said members from said engagement to permit movement of the valve-supporting member to an advanced position by said pressure, a spring

operatively associated with said members independently of the force applying means and normally retaining the members in engagement, said spring thereby acting in opposition to said release force when applied from the external source to disengage the members, means for adjusting the spring to regulate the resistance thereon to said relative displacement, and antifriction means on one of said members forming a seat for the other member so as to reduce to a minimum the friction opposing said displacement.

3. Emergency trip mechanism for valves, said mechanism comprising a pressure-biased valve-supporting member constrained to move in a rectilinear path, a lever having a pivotal connection intermediate its ends with said member and extending transversely to said path of movement of the latter, a pivotal support for one end of said lever, a second lever pivotally supported adjacent the other end of the first-named lever and having thereon a seat for the proximate end of the latter whereby to support the valve-supporting member in retracted position against the said pressure bias, means for applying force from external source divorced from said first-named lever to pivotally move said second lever to displace the said seat in a direction approximately longitudinally of and away from the seated end of the first-named lever to thereby release the latter, a spring operatively associated with said second-named lever independently of the displacing means and normally retaining said lever in operative position supporting the second-named lever, said spring thereby acting in opposition to said release force when applied from the external source to move said second lever, and means for adjusting the spring to regulate the resistance thereof to said displacement.
